CLARE H. DRAPER, OF HOPE DALE, MASSACHUSETTS, ASSIGNOR, BY MESNE ASSIGNMENTS, TO DRAPER CORPORATION, OF HOPE DALE, MASSACHUSETTS, A CORPORATION OF MAINE.

SHUTTLE-TENSION-CONTROLLING MECHANISM FOR LOOMS.

Application filed December 18, 1925. Serial No. 76,204.

The present invention relates to an improvement in shuttle tension controlling mechanism for looms.

The present construction is an improvement on the construction of the patent to Draper & Northrop, No. 1,556,207, dated October 6, 1925. The invention consists in the construction hereinafter described and particularly defined in the claims.

10 In the accompanying drawings illustrating the preferred form of the invention, Fig. 1 is a sectional elevation of the lay and associated parts; Fig. 2 is a detail showing the inertia arm and its connection with the 15 dagger shaft; and Fig. 3 is a section taken on the line 3—3, Fig. 2.

The illustrated embodiment of the invention is described as follows: The lay 10 is supported on the swords 11, provided with 20 the shuttle box 12, adapted to receive a shuttle. The shuttle binder 14 is of the usual form, and is activated by the binder fingers 15 to cause pressure to be exerted upon the shuttle in the box. The shuttle 25 fingers are mounted on the arms 16 of the dagger shaft 17, mounted in brackets on the lay in the usual manner and encircled by a coil spring operating to tend to turn the shaft in the direction to depress the dagger 30 as is usual. The dagger 18 is carried by the dagger shaft 17, and adapted to engage the steel 19 of the frog 20 in the usual manner. An inertia arm 21 is loosely mounted on the 35 dagger shaft 17, as shown in Fig. 2, and carries the weight 22 secured to it. The hub 23 of the inertia arm is held from movement to the left, as viewed in Fig. 2, by means of the collar 24, which is secured on the dagger shaft 17. Movement in the opposite 40 direction to the right, as viewed in Fig. 2, is prevented by the collar 25, which is secured on the dagger shaft 17 by a set screw. The collar 25 is provided with the 45 dagger stop 26, adapted to engage the plate 27 on the under side of the lay 10, for the purpose of preventing overthrow of the dagger, as is usual.

In the construction illustrated in said patent, the movements of the dagger shaft, 50 binder fingers and associated parts are controlled by their weight, the binder shaft spring, and the weight of the inertia arm, as described therein, but during the first part of the forward movement of the lay

the binders were, in addition, urged inward by the inertia arm, with the result that the binder and shuttle were subjected to unnecessary wear.

According to the present invention the inertia arm 21 is provided with a stop 28, 60 which is formed integral with the inertia arm and is adapted to engage the lay, as shown in Fig. 1, thereby preventing it from urging the binder fingers inwardly during the first part of the forward movement of 65 the lay.

Connections between the inertia arm and the dagger shaft permit a slight oscillatory motion of the inertia arm on the dagger shaft by reason of the fact that the sleeve 70 25 and the hub 23 have interlocking portions, as shown in Fig. 2. That is to say, the upper half of the right hand end of the hub 23 of the inertia arm is cut away to receive the interlocking extension 29 of the sleeve 25, 75 and the lower right hand portion 30 of the hub 23 constitutes an extension which is received in what may be termed for convenience, the cut-away portion of the sleeve 25. By reference to Fig. 3 it will be seen that the 80 extension 29 and the extension 30 afford a permissible, free movement of the inertia arm with respect to the dagger shaft of about 30°. Connected to the extension 29 by a broken line is shown the binder finger 15, 85 which parts are rigidly connected together, as the dagger sleeve 25 is rigidly secured to the dagger shaft, which rigidly carries the dagger finger. Similarly the extension 30 is shown as connected by a broken line with 90 the inertia arm 21 to which it is rigidly attached, being made integral therewith, and the stop 28 is also shown as connected by a broken line with the extension 30, with which extension it is integrally formed. It is also 95 shown in engagement with the lay 10.

The operation of the mechanism of this application is identical with the operation of the mechanism of the said patent, with the exception that during the first part of 100 the forward movement of the lay from back center, as it starts to move forward from back center and until the shuttle is received in the box, the action of the inertia arm on the binder fingers is prevented by the engagement of the inertia arm stop 28 with the lay. At this time the face 31 of the extension 30 of the inertia arm hub 23 does not

exert any pressure on the face 32 of the extension 29 of the dagger shaft sleeve 25, and it is inoperative, therefore, to exert any effect on the dagger shaft tending to cause the 5 binder fingers to move the binders into the shuttle box beyond the position as determined by the dagger shaft spring. The movements of the lay backward and forward cause variation in the dagger shaft 10 control by the inertia arm 21 and its attached weight and consequently variations in the binder pressure. Assuming the lay to be in front position and starting on its backward movement, rearward motion is imparted to 15 the inertia arm by the lay, but the inertia of the weight 22 causes said weight to take up the accelerating rearward movement of the lay more slowly than the lay itself, with the result that the weight 22 and lay will 20 have a relative movement and effect relief of pressure of the dagger fingers on the binders during part of the lay rearward movement or until the lay has reached about top centre. Since the shuttle is picked at about 25 top centre, the binder pressure on the shuttle is thus released at the picking point. As the lay passes back centre and starts forwardly its movement is accelerated until bottom centre is reached and is then gradually 30 diminished until the lay reaches front centre where its movement is arrested, and since the inertia arm and weight are carried by the lay, the stop 28 engages the lay as the latter starts forward, and as front centre is 35 reached by the lay with gradually diminishing velocity until it comes to rest, the inertia of the inertia arm and weight effects relief of binder pressure as the lay reaches front centre and therefore at the time of bobbin 40 transfer which is effected at substantially this point in the lay movement.

When the lay is at back center, as indicated by Figs. 1 and 3, the stop 28 of the inertia arm engages the lay, as shown, and 45 such engagement continues as the lay moves forwardly, and since the face 31 of the inertia arm hub 30 does not press upon the face 32 of the extension 29 of the dagger sleeve because of the engagement of the stop 50 28 with the lay, the inertia arm is prevented from acting through the dagger sleeve or dagger rod during forward movement of the lay, but as the lay slows down and finally stops at front position, while the inertia arm 55 continues under its inertia to swing forwardly, the gap shown at the right of Fig. 3 is closed and the inertia arm then acts through the extension 29 of the dagger sleeve to relieve the binder pressure.

60 Having thus described the invention, what is claimed is:

1. Shuttle box tension controlling mechanism for weft replenishing looms of the bobbin changing type having, in combination, 65 a lay, a shuttle, a binder, a spring actuated

dagger rod on the lay, binder fingers on the dagger rod, an inertia arm on the dagger rod provided with a weight below the dagger rod, and means for preventing the inertia arm and weight from acting on the binders during 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295
